UNITED STATES PATENT OFFICE.

ISAAC F. SCULLIN, OF WASECA, MINNESOTA.

DESIGN FOR A BEAD RING.

No. 39,049.

Specification for Design.

Patented Feb. 4, 1908.

Application filed November 6, 1907, Serial No. 401,031. Term of patent 7 years.

To all whom it may concern:

Be it known that I, ISAAC F. SCULLIN, a citizen of the United States, residing at Waseca, in the county of Waseca and State of Minnesota, have invented a new, original, and ornamental Design for Bead-Rings, of which the following is a specification, reference being had to the accompanying drawing, forming a part thereof.

The figure on the drawing is a perspective view of a bead ring showing my new design.

I claim:

The ornamental design for a bead ring, as shown.

ISAAC F. SCULLIN.
